UNITED STATES PATENT OFFICE.

MOSES O. NICHOLS, OF CLYDE, OHIO.

IMPROVEMENT IN REED-ORGAN REEDS.

Specification forming part of Letters Patent No. **144,409**, dated November 11, 1873; application filed July 5, 1873.

To all whom it may concern:

Be it known that I, MOSES O. NICHOLS, of Clyde, in the county of Sandusky, Ohio, have invented a new and useful Improvement in Reed-Blocks for Reed-Organs, of which the following is a specification:

My invention consists in the novel construction of the reed-block and reed of cabinet-organs, harmoniums, &c., as hereinafter described. The advantages of my improvement are, first, the production of a full round tone, very closely resembling that of the pipe-organ; secondly, it admits of the use of a very thin reed, that secures the quality of a perfected vanish in the power of the tone, by the suppression of the wind-supply; and, thirdly, it has the property of uttering the tone with exceeding rapidity, and is, therefore, a wonderful improvement in the matter of executing the will of the performer. It also furnishes a proper accompaniment to the more delicate tones of the manual of the organ, inasmuch as the tones do not vary in pitch while receding or accumulating in power.

This device is illustrated in the accompanying drawing, in which is presented a superficial view thereof, Figure 1 being a plan, and Fig. 2 an edge view.

In order that others skilled in the art may be enabled to use my invention, I will describe its construction and method of application.

I take a metallic wire and bend it to the

curvature described in the accompanying drawing, and marked A. I then make a flat bar of brass, of the size of that portion of the reed-tongue which we call the heel, and which is marked B. This is fastened across the end of the reed-block by any method desired. It may be fastened with solder, or cut into the block with a slot or dovetail, and pressed to place under a swaging-tool, or the reed-tongue may be inserted in that manner without the use of a heel-piece. When a heel-piece is used, the reed-tongue is fastened to it in the usual form, by riveting.

I use a reed-board of the common form, cutting the receiving-slide in the reed-cell to conform to the diameter of the wire used in making the reed-block. The reed is tuned and used in the same manner as other reeds.

The vibrating end of the reed is shown at C in the drawing.

I claim—

1. The reed-block A, formed of bent wire, substantially as and for the purpose described.
2. The wire reed-block A, in combination with the heel-plate B, substantially as described.
3. The wire reed-block A, in combination with the heel-plate B and tongue C, when constructed substantially as described.

MOSES O. NICHOLS.
